ATTORNEY.

UNITED STATES PATENT OFFICE.

THOMAS R. EVANS, OF PHILADELPHIA, PENNSYLVANIA.

SHOE.

SPECIFICATION forming part of Letters Patent No. 338,144, dated March 16, 1886.

Application filed August 22, 1885. Serial No. 175,031. (No model.)

To all whom it may concern:

Be it known that I, THOMAS R. EVANS, a citizen of the United States, residing in the city and county of Philadelphia, State of Pennsylvania, have invented a new and useful Improvement in Shoes, which improvement is fully set forth in the following specification and accompanying drawings, in which—

Figure 1 represents a side elevation of a shoe embodying my invention. Fig. 2 represents a perspective view thereof. Fig. 3 represents a section in line x x , Fig. 1. Fig. 4 represents a perspective view of a portion of a modification.

Similar letters of reference indicate corresponding parts in the several figures.

My invention consists in attaching the flap of a shoe to the vamp by forming slits in the vamp and inserting the lower end of the flaps between the walls of the slits, and then stitching the flaps to said walls.

It also consists in attaching the flaps to the vamp by inserting the lower end of the flaps in the slits in the vamp, and providing the vamp with gussets which are located adjacent to said slits, so as to improve the fit of the vamp and avoid crimping of the upper.

Referring to the drawings, A represents the vamp of a shoe, and B the quarters thereof, all formed of one piece of leather.

C C' represent the flaps of the shoe, the lower ends of the forward portions thereof being fitted in slits D, made in the vamp near the top thereof, the lower ends of the remaining portions of the flaps being secured to the upper ends of the quarters. The lower ends of the forward portions of the flaps are secured

to the vamp by a row of stitches, E, which pass through the flaps and walls of the slits D, and another row of stitches, F, above the row E, thus employing a double row of stitches for securing the flap to the vamp, making an exceedingly strong connection of said parts.

G represents a gusset in the tongue edge at the top of the vamp; or there may be a gusset on each side of the tongue adjacent to the slits D, by which provision the crimping of the upper is avoided and the shoe is rendered flexible at the instep, thereby making a better and easier fit.

Having thus described my invention, what I claim as new, and desire to secure by Letters Patent, is—

1. A shoe having slits D in the vamp or quarters thereof, and flaps fitted between the walls of said slits and secured thereto, substantially as described.

2. A shoe having slits D in the vamp or quarters thereof, and flaps fitted between the walls of said slit and secured thereto, and a gusset or gussets connected with said vamp or quarters adjacent to said slits, substantially as described.

3. The vamp and quarters formed in one piece, with the slits D in the vamp, in combination with the flaps fitted in said slits and secured to the walls thereof, and the gussets G, connected with the vamp adjacent to the slits, substantially as described.

THOS. R. EVANS.
